Fig. 3.

Fig. 4.

Fig. 5.

This application is a continuation-in-part of our earlier design application Ser. No. 5,800, filed Feb. 13, 1967, now abandoned.

FIGURE 1 is a perspective view of an insulated portable chest showing our new design;

FIG. 2 is a side elevational view;

FIG. 3 is an elevational view showing the end opposite to the end shown in FIG. 1;

FIG. 4 is a bottom plan view; and

FIG. 5 is an enlarged fragmentary view of a portion of the top showing the handle partially raised.

We claim:

The ornamental design for an insulated portable chest, as shown and described.
